JASPER CLAY COATES, OF SANTA PAULA, CALIFORNIA, ASSIGNOR TO WARREN CROCKER AND H. G. BENISON, BOTH OF VENTURA COUNTY, CALIFORNIA

FRUIT WASHING MACHINE

Application filed July 20, 1927. Serial No. 207,231.

My invention relates to fruit washing machines and more particularly to those machines employing a rotary bottom brush table and side and top brushes all arranged to provide a plurality of runways for fruit, the latter being propelled through the runways under rotary movement of the brush table.

In machines of this character the side brushes are secured to the side frames by means of screws and consequently to remove the brushes when they become worn for the substitution of new brushes involves a tedious and time-consuming operation which requires a discontinuance in operation of the machine.

It is a purpose of my invention to provide in a fruit washing machine a mounting for the side brushes which permits the removal and replacement of the brushes with such a degree of dispatch that discontinuance in operation of the machine is unnecessary, and hence the attendant loss in time and labor is eliminated.

In machines of the foregoing character the top brushes are weighted and suspended by chains connected to the brush backs by eyes. When any one of the top brushes is rendered useless by reason of excessive wear it is necessary in discarding the worn brush to likewise discard the corresponding weight and eyes as they are permanently incorporated in the brush-back structure. To eliminate the loss resultant of such a brush structure in respect to the weight and eyes my invention has for a second purpose, the provision of a mounting for a top brush in which the weight and eyes are independent of the brush-back and the brush is detachably secured to the mounting so that the brush can be discarded independently of its mounting without the necessity of discarding the weight and eyes so that the latter can be retained indefinitely for use with the new brushes.

I will describe only one form of fruit washing machine embodying my invention and will then point out the novel features in claims.

In the accompanying drawings:

Fig. 1 is a view showing in top plan one

form of fruit washing machine embodying my invention;

Fig. 2 is an enlarged vertical sectional view taken on the line 2-2 of Fig. 1;

Fig. 3 is an enlarged plan view of a pair of the top brushes shown in preceding views and their mountings;

Fig. 4 is a vertical sectional view taken on the line 4-4 of Fig. 3;

Fig. 5 is a view showing in perspective one of the mountings for the side brushes of the machine.

Referring specifically to the drawings in which similar reference characters refer to similar parts in each of the views, my invention in its present embodiment is incorporated in a well known type of fruit washing machine which essentially consists of a rotary table T rotatable on a shaft S and carrying bottom brushes B. The table is rotatable in a housing H provided with an opening 15 through which the fruit to be cleaned is introduced onto the brushes B from a platform P. Within the housing and above the brushes B are partitions A, A' and A² which are disposed concentrically of each other and the housing H with their ends terminating flush with the ends of the housing so as to form in effect a continuation of the opening 15. A partition 16 rises from the platform P so as to divide the opening 15 into entrance and exit openings for the fruit, with partitions 17 and 18 extending from the ends of the partitions A and A' to direct the fruit into the channels or runways provided by the partitions A, A', and A², and to effect discharge of such fruit from the table-back onto the platform P after the fruit has traversed the channels or runways.

At the inner sides of the partitions A' and A² side brushes B' are arranged so as to have scrubbing engagement with fruit traversing the channels or runways. These brushes are secured to the partitions by mountings, and these mountings are detachably secured to both the brushes and the partitions. For the partitions A' and A² as many such mountings are provided as are necessary to mount the required number

of brushes to form a continuous brushing surface throughout the length of the partitions, and as the construction of the several brushes and mountings is the same a description of one will suffice for all.

As shown in Figs. 2 and 5, each mounting comprises a single length of sheet metal or other suitable material bent to provide a body 20 corresponding in curvature to the partition to which it is attached. The longitudinal edges of the body are formed with right-angular flanges 21 and 22, the upper flange being of greater width than the lower flange, and both flanges terminating at their outer edges in reversely bent lips 23 and 24, respectively. The flanges 21 and 22 are split at intervals as indicated at 25 in order that the body 20 may be bent to its arcuate form. Portions of the flange 21 are bent outwardly to provide hooks 26 by which the mounting as a whole is attached to the corresponding partition as clearly illustrated in Fig. 2.

Each side brush B' comprises a back 27 in which bristles 28 are secured. One transverse edge of the back 27 is formed with a groove 29 for the purpose of receiving the lower lip 24. In applying the brush to the mounting the upper end of the back 27 is slid into the groove provided by the flange 21 and the lip 23, while the lower end is applied so that the lip 24 engages within the groove 29. In this manner the brush is secured to the mounting yet capable of adjustment longitudinally thereon in order that the mounting may accommodate other brushes. The ease with which the brushes may be applied to or removed from the mounting will be apparent, and likewise the ease with which the mounting as a whole can be applied to or removed from its respective partition. In the applied position of the mounting, as illustrated in Figs. 1 and 2, the hooks 26 engage the upper edge of the partition A' or the partition A'', and in either instance the several brushes are held contiguous to the inner side of the partition to present a substantially uninterrupted brushing surface to the fruit moved forwardly under the rotative action of the bottom brushes B.

The fruit washing machine also includes top brushes B² suspended from curved frames F by means of hooks 30 and chains 31 engaging within eyes 32. By reference to Fig. 2 it will be seen that there are two sets of brushes, one for each of the channels or runways, and these brushes are adapted to coact with the side and bottom brushes in the cleaning of fruit as it is moved through the runways. The brushes B² are detachably associated with the chains 31 by the provision of mountings 33 to which the eyes 32 are secured. As shown in Fig. 4, each mounting 33 is made of a plate of metal or other suit-

able material having its longitudinal edges provided with flanges 34 bent to form grooves in which the brush-back is partly received. The flanges in turn are formed with lips 35, preferably coextensive in length therewith and designed to engage within grooves 36 of the brush-back. In this manner the brush is detachably secured to the mounting to permit the substitution of new brushes when required.

The top brushes B² are preferably weighted in order that they may properly function in their association with the side and bottom brushes to effectively clean fruit. As in previous machines the brushes are hingedly connected to each other in order that they may be maintained against relatively lateral displacement and yet be free to move vertical in response to variation in the size of fruit handled by the machine. To hingedly connect any two adjacent brushes eyes 37 are secured to the flanges 34, and pins 38 are extended through the eyes at the confronting sides of any two mountings thereby providing the hinged connection.

To weight the top brushes, each brush is provided with a weight 39 secured to the mounting 33 and provided with openings 40 through which the shanks of the eyes 32 are extended. From this construction it will be seen that the eyes 32 and 37 as well as the weight 39 are all carried by the mounting 33 and independently of the brush B². Consequently, when it is desired to discard the brush B², such as when it becomes excessively worn, it can be readily removed from the mounting by sliding the latter longitudinally therefrom. It is unnecessary to disconnect the mounting for the brush from the mounting of the adjacent brushes, nor is it necessary to disconnect the chains from the frames. With the worn brush removed, a new brush can be readily substituted and applied to the mounting.

Although I have herein shown and described only one form of fruit washing machine embodying my invention, it is to be understood that various changes and modifications may be made herein without departing from the spirit of the invention and the spirit and scope of the appended claims.

I claim:

1. A brush mounting of the character described comprising a body having lipped flanges defining grooves for receiving the backs of brushes, and hooks positioned to have hooked engagement with a support and disposed on the body to suspend the latter in a vertical position from the support.

2. A mounting for top brushes of fruit washing machines comprising a brush having its back provided with grooves, a plate, flanges projecting laterally from opposed side edges of the plate, lips on the flanges adapted to be received in the grooves of the

brush back to detachably secure the brush to the plate, eyes on the plate to which chains are adapted to be connected, and other eyes on said flanges through which pins are adapted to be inserted to hingedly connect the plate to other plates.

3. A mounting for top brushes of fruit washing machines comprising a brush having its back provided with grooves, a plate, flanges projecting laterally from opposed side edges of the plate, lips on the flanges adapted to be received in the grooves of the brush back to detachably secure the brush to the plate, eyes on the plate to which chains are adapted to be connected, other eyes on said flanges through which pins are adapted to be inserted to hingedly connect the plate to other plates, and a weight adapted to rest upon the plate and having openings receiving the first mentioned eyes to secure the weight to the plate.
